UNITED STATES PATENT OFFICE

PATRICK J. KELLY, OF CHICAGO, ILLINOIS

COMBINED REFRIGERATING AND FREIGHT CAR

Application filed June 21, 1928. Serial No. 287,290.

My invention relates to improvements in refrigerating equipment for freight cars, which is of a design to permit the use of the car for freight in one direction of its trip, 5 and for food stuffs and other perishable goods in the return direction.

I am aware of the fact that improvements for this purpose have been devised in the past, but these have apparently been deficient, as they have failed to gain popularity.

The main object of my invention is to design the refrigerating unit for compact installation in each end of the car, whereby to 15 leave a maximum amount of room for the goods.

A further object of the invention is to construct the refrigerating unit with peculiar means to induce a circulation of cold and 20 warm air in the car, with the effect of maintaining the goods under a cold temperature at all times.

A still further object of the invention is to provide a simple means for shielding the 25 refrigerating units in the car in case the latter is to be used for freight or nonperishable goods, such as grain.

Another object of the invention is to provide a purifying agent in connection with 30 the refrigerating units, whereby impurities in the atmosphere within the car may be absorbed without necessitating the ventilation of the car with air from the outside.

A final, but nevertheless important object 35 of the invention is to construct the novel refrigerating means with utmost simplicity, so that the equipment may not add materially to the cost or maintenance of the car.

With the above objects in view and any 40 others that may suggest themselves in the specification and claim to follow, a better understanding of the invention may be gained by reference to the accompanying drawing, in which—

45 Figure 1 is a cross section of the car, showing the refrigerating unit in one end thereof; and

Fig. 2 is a vertical section of such end, taken on the line 2—2 of Figure 1.

50 Referring specifically to the drawing, 5

denotes the side walls, 6 the roof, 7 the floor and 8 the end walls of a typical freight car. For the use of the latter also as a refrigerating car, I double the walls thereof as indicated at 9 as well as in other necessary 55 places to receive vacuum units, so as to retain the temperature in the car for long periods. I do not claim invention for this expedient; nor for other means for sealing the car to retain its temperature, such as doors, fittings 60 and the like.

In each end of the car I install a refrigerating unit in the form of a box 10, which extends the full width of the car. The box is constructed preferably of heavy galvanized 65 sheet metal and is provided at the top with a loading neck 11, fitted with a lid 12. On the front and rear are wood gratings 12^a, and at the bottom is installed a drain board 13, the bottom being sunk to form a gutter 14 70 into which the water draining from the ice may accumulate. When this occurs to a given height, a trap 15 comes into play to lead the excess into a discharge pipe 16 while creating a seal against the rise of atmospheric 75 or warm air through the discharge pipe into the refrigerating unit. Thus, water to a certain level is always present in the gutter 14 and this makes for the purification of the atmosphere within the car. It is an established fact that an open vessel of water 80 absorbs atmospheric impurities.

The inner wall of the refrigerating unit is formed with several horizontal series of perforations 16. One of these series is near the 85 top, while the balance of the series commences about one-third way down, continuing to the bottom. In front of the perforated wall a set of deflector plates 17 is applied opposite the several series of perforations 16. 90 The top deflector plate opens in an upward direction, while the balance of the deflector plates open downwardly. No deflector plate is provided or considered necessary for the lowermost series of perforations.

In front of the refrigerating unit and spaced therefrom is an assembly of gates 18, which are hinged to the car at the outer ends as indicated at 19. The gates close at the middle and are secured by a latch 20 from 95 100

one gate closing into a keeper 21 carried by the other gate. The gates are shown closed, and when in this position, the car may receive a load of grain or other freight without interfering with the refrigerating units in its ends. Ordinarily, grain is piled only to a partial extent, so that the gates need not be high to shield the refrigerating units; however, in case the height of the freight is greater, the gates can be made higher, this being merely a matter of circumstance under one or another condition.

When the car is to be used for refrigerating purposes, the gates 18 are opened wide and the refrigerating units filled with ice. The air chilled by the ice will naturally seek escape from the units at low levels through the series of perforations 16. The downward passage of air as it emerges from the refrigerating unit will be aided by the downwardly deflected plates 17, so that this chilled air emerges from the unit at each end of the refrigerator and courses through the area in which the food stuffs or other perishable freight are located. Conversely, the warm air usually in the upper part of the car will be forced to seek escape laterally, and will enter the refrigerating chambers through the top series of perforations 16 by way of the upwardly deflected plates 17. As the warm air from the food stuffs keeps rising from the effect of its being displaced, the process just described will continue, so that a circulation will be maintained within the car at all times. As stated before, the water gutters 14 will serve to absorb impurities from the atmosphere of the car and the trap 15 will prevent warm air from rising into the same, thus making it unnecessary for external air to be admitted into the car in order that the atmosphere in the latter may be kept clean and fresh. It will be obvious that the admission of such air is detrimental to the cooling effect of the refrigerator units and makes the operations thereof wasteful in two ways, that is, the food stuffs are not apt to be maintained at a sufficiently cold temperature, and the supply of ice will require more frequent renewal.

The structure described above typifies a self-contained refrigerating car, which is however readily changeable into a freight car and vice versa. As noted, no moving parts or delicate mechanism are involved to prejudice the action of the equipment or cause it to get out of order. The parts used are few and simple, and the cost to build the units and install them should be low. I have thought it unnecessary to design or illustrate any additional equipment which would be advisable to complete the installation for the most efficient operation, since additional equipment is easily within the skill of the refrigerating engineer who is specialized in the field of refrigerating cars.

I claim:

A combined refrigerating and freight car comprising a refrigerating chamber in said car characterized by a wall having passages for permitting air in the car to circulate through the refrigerating chamber, means forwardly of the wall for deflecting air issuing from the refrigerating chamber, ice supporting means mounted substantially in the plane of the bottom of the car, a shallow drainage receptacle below said ice supporting means corresponding in size to the bottom of the refrigerating chamber and adapted to contain water and expose a relatively large surface of the same for the absorption of impurities from the refrigerating chamber, and means for controlling the quantity of water in said drainage receptacle and gates positioned forwardly of the deflecting means for shielding said passages, said gates being pivoted at the side of the car and swingable out of the way to permit the car to be used for freight.

In testimony whereof I affix my signature.

PATRICK J. KELLY.
